UNITED STATES PATENT OFFICE.

LOUIS T. BULLEY, OF WEST HAVEN, CONNECTICUT, ASSIGNOR TO C. COWLES & CO., OF NEW HAVEN, CONNECTICUT, A CORPORATION.

SEPARABLE FASTENER.

REISSUED

1,246,868.

Specification of Letters Patent. Patented Nov. 20, 1917.

Application filed July 3, 1917. Serial No. 178,332.

To all whom it may concern:

Be it known that I, LOUIS T. BULLEY, a citizen of the United States, residing at West Haven, in the county of New Haven 5 and State of Connecticut, have invented a new and useful Improvement in Separable Fasteners; and I do hereby declare the following, when taken in connection with the accompanying drawings and the characters 10 of reference marked thereon, to be a full, clear, and exact description of the same, and which said drawings constitute part of this application, and represent, in—

Figure 1 a plan view of the socket-member of a separable fastener constructed in accordance with my invention and shown as attached to a curtain.

Fig. 2 an underside view of the socket-member, detached.

Fig. 3 an inside view of the front-plate, slide and spring, with the back-plate detached.

Fig. 4 a longitudinal sectional view showing the socket-member engaged with the post 25 and in the locked position.

Fig. 5 a similar view showing the socket tilted to unlock the slide from the post.

Fig. 6 a perspective view of the slide, detached.

Fig. 7 a perspective plan view of the back-plate, detached.

This invention relates to an improvement in separable fasteners, and while adapted for various purposes, is especially designed 35 for use as a curtain fastener. In the more general construction of fasteners of this type, the socket member includes a wire which is adapted to directly engage with a post.

40 The object of this invention is to provide a sheet-metal slide which will positively engage with the post so as to interlock the socket therewith, and to provide that slide with a finger adapted to engage with the post and move the slide when the socket is turned in one direction; and the invention consists in the construction hereinafter described and particularly recited in the claims.

50 In carrying out my invention, the socket-member 8 comprises a back-plate 9, a front-plate 10, a slide 11, and a spring 12. The back-plate is formed around its edge with two series of slots 14 and 15 through which 55 project fingers 16 and 17 on the front-plate

10, the fingers 16 being turned down over the back-plate 9 so as to interlock the front-plate with the back-plate, the front-plate being slightly cup-shaped so as to form a chamber 18 between them. The fingers 17 60 form prongs by which the socket-member may be attached to a curtain 19. The back-plate is also formed with a central opening 20 in one side of which is a notch 21 for the purpose as will hereinafter appear. 65 The front plate 10 is formed with a central recess 22 in line with the opening 20 in the back-plate. The slide 11 is located between the front and back-plate and is formed with a clearance-opening 23 corresponding to the 70 opening 20, and with a projecting cam-finger 24 which extends through the notch 21 in the back-plate and is slightly curved so as to engage with one side of a post 13. This post 13 is formed with an annular 75 groove 25 the outer wall of which forms a bearing-shoulder 26 for the slide 11. Within the chamber 18 is an S-shaped spring 12 which bears against the wall of the front plate and against the edge of the slide 11, 80 normally tending to crowd the finger 24 against the post 13, as shown in Figs. 4 and 5 of the drawings. The socket-member is engaged with the post by passing it over the outer end of the post, the slide moving 85 against the pressure of the spring to permit the head of the post to pass through the openings 20 and 23. As soon as the socket is moved onto the post sufficiently the slide will spring into the annular groove 25 and 90 thereby firmly interlock the socket with the post. In order to move the slide out of engagement with the post, it is necessary to lift one end of the socket so as to cause the finger 24 acting like a cam, to move the slide 95 so as to bring the opening 23 into line with the opening 20, and permit the socket to be lifted off from the post. As will be seen by Fig. 5 of the drawings, the tilting of one side of the socket crowds the finger 24 100 against the side of the post so as to move the slide with respect to the front and back-plates. It will thus be seen that while the socket may be readily detached from the post when the socket is tilted in one direction, the socket will be positively interlocked with the post against movement in any other direction. By using a sheet-metal locking slide a more rigid engagement is made between the socket and the post than is possi- 110

ble when wire springs are employed to form the lock.

While I prefer to form the front plate with the recess 22 to give clearance for the 5 head of the post, as in this way the mechanism is completely housed and the possibility of dirt and water entering the fastener is avoided, it is obvious, without further illustration, that instead of forming the 10 front plate with a recess, it might be formed with a perforation to allow for the clearance of the head.

I claim:

1. In a separable fastener, a socket-member comprising front and back-plates, a sheet-metal slide located between the front and back-plates and provided with a finger projecting outward through the back-plate, and a spring between the front and back- 20 plates and bearing against the said slide.
2. A separable fastener comprising a socket-member including a front and back-plate, a sheet-metal slide located between the front and back-plates, said back-plate 25 and slide each formed with perforations, the slide formed with a finger projecting outward through the back-plate, combined with a post formed with an annular groove and

adapted to extend through the perforations in the back-plate and slide, the slide adapted 30 to enter the groove in the post, and the finger on the slide engaged with the side of the post.

3. A separable fastener comprising a socket-member including a front and back-plate, 35 a sheet-metal slide located between the front and back-plates, said back-plate and slide each formed with perforations and the front-plate formed with a recess in line with the perforation in the back-plate, the slide 40 formed with a finger projecting outward through the back-plate, combined with a post formed with an annular groove and adapted to extend through the perforations 45 in the back-plate and slide, the slide adapted to enter the groove in the post, and the finger on the slide engaged with the side of the post.

In testimony whereof, I have signed this 50 specification in the presence of two subscribing witnesses.

LOUIS T. BULLEY.
